J. A. FRIEND

DRAIN VALVE FOR DEEP WELL PUMPS

Filed April 21, 1927

UNITED STATES PATENT OFFICE.

JOHN A. FRIEND, OF NORPHLET, ARKANSAS.

DRAIN VALVE FOR DEEP-WELL PUMPS.

Application filed April 21, 1927. Serial No. 185,532.

This invention relates to drain valves, and has for one of its objects to provide a novel, simple and highly efficient device of this character which shall be especially adapted for use in connection with the inner tube of a deep well pump and which shall embody a lever adapted to be actuated by the well casting during the withdrawal of the inner tube so as to effect the opening of the valve and 10 the draining of the inner tube during its withdrawal.

With the foregoing and other objects in view, the nature of which will become apparent as the description proceeds, the invention 15 consists of the construction, combination and arrangement of parts hereinafter fully described and claimed, and illustrated in the accompanying drawing, wherein:

Figure 1 is a vertical sectional view illustrating the application of the drain valve, the valve being closed,

Figure 2 is a similar view with the valve opened,

Figure 3 is a sectional view taken on the 25 horizontal plane indicated by the line 3—3 of Figure 1, and

Figure 4 is a similar view taken on the horizontal plane indicated by the line 4—4 of Figure 1.

The casings and inner tubes of deep well pumps are of sectional formation, and the sections thereof are connected by couplings with the proximate ends of the casing sections in relatively spaced relation. It is frequently necessary to withdraw the inner tubes of deep well pumps, and to facilitate their withdrawal the valve is adapted to effect their draining during the initial phase of their upward movement with respect to 30 the casings.

To illustrate the application of the valve and the manner in which it is adapted to be opened, there is shown in the drawing two sections of the casing and one section of the inner tub of a deep well pump, the casing sections being designated 1 and 2, the coupling thereof 3, and the tube section 4. The valve comprises a casing 5 which is arranged vertically on the outer 50 side of the tube section 4 and which may be formed integrally with said section or made separately and attached thereto in any suitable manner. The lower portion of the bore or passage 6 of the casing 5 is radially enlarged, as shown at 6^a, for the reception of a plug 7. A polygonal boss 8 is

formed on the lower end of the plug 7 to permit of its ready application to or removal from the casing 5. The plug 7 is provided in the upper portion thereof with a passage 9 which communicates with the upper portion 6^b of the passage 6 and which is similar in diameter to said passage portion. A ring 10 which is provided at its lower edge with a valve seat 11, is positioned in the passage 6^b portion 6^b and the passage 9, and is provided with an outer flange or rib 12 clamped between the upper end of the plug 7 and the shoulder 13 at the juncture of the passage portions 6^a and 6^b. The casing 5 is provided with an outlet port 14 which extends radially therethrough and communicates with the passage portion 6^b. The plug 7 is provided with an intake port 15 which extends radially therethrough and communicates with the passages 9 and with an opening 16 formed in the side of the tube section 4. The discharge port 14 is located above and the intake ports 15 and 16 below the valve seat 11. A ball valve 17 is arranged in 80 the passage 9, and is adapted to be normally held against the seat 11 by a coil spring 18.

The casing 5 is provided above the passage 6 with a bore 19, and is provided above the bore with relatively spaced lugs 20 which have horizontal slots 21. A plunger 22 is slidably mounted in the bore 19, and is provided with a reduced lower end 23 which rests upon the ball valve 17. A lever 24 is connected to and between the lugs 20 for pivotal and radial movements, and is supported for these movements by a pin 25 which passes therethrough and has its ends positioned in the slots 21. The lever 24 is normally held against movement with respect to the casing 5 by means of a leaf spring 26 which is positioned between the lugs 20 and between the inner end of the lever and the tube section 4. The lever 24 rests upon the upper end of the plunger 22 and is normally supported by the spring 26 in an upwardly and outwardly inclined position with respect to the plunger. The lever 24 is provided with a sharpened outer end and below and inwardly of said end with a cam 95 lug 27.

In practice, the lever 24 will normally occupy an upwardly inclined position with its free end in contact with the inner surface of one of the casing sections 1, its pivot pin 25 will occupy the inner ends of the slots 21, and the spring 26 will be under

compression, all as shown in Figure 1. As the lever 24 is constantly urged in the direction of the casing by the spring 26, its free end will be forced into the space between the proximate ends of two of the casing sections during the initial phase of the withdrawal movement of the inner tube. During the next phase of the withdrawal movement of the inner tube, the free end of the lever 24 will contact with the end of the upper of said tube sections, and be rocked in a downward direction. This movement of the lever 24 causes the cam 27 to contact with the upper end of the plunger 22, with the result that the plunger will be moved downwardly and the ball valve 17 unseated. These parts will remain in these positions until the inner tube has been fully withdrawn. The ball valve 17 will thus be held unseated, and the liquid in the inner tube will flow therefrom into the casing by way of the ports 16 and 15, passages 9 and 6 and discharge ports 14. Should the lever 24 be in plunger depressing position when the inner tube is again lowered into the casing, it will be returned to its normal position by and as the result of its engagement with an end of one of the casing sections.

If desired the lever 24 may be constructed so as to engage the inner surface of one of the casing sections, and be rocked downwardly as the result of such engagement during the initial phase of the withdrawal movement of the inner tube.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. In combination, a well casing, a tube therein, a normally closed drain valve carried by the tube, and a valve opening lever carried by the tube and engaging the casing.

2. In combination, a well casing, a tube therein, a normally closed drain valve carried by the tube, a valve opening lever connected to the tube for pivotal and radial movements with respect thereto, and a spring normally urging the lever radially outward with respect to the tube.

3. In combination, a well casing, a tube therein, a normally closed drain valve carried by the tube and provided with radial

slots, a valve opening lever having a pivot pin positioned in said slots, and a spring positioned between the lever and tube. 60

4. In combination, a well casing, a tube therein, a valve casing carried by and communicating with the tube, a normally seated valve within the valve casing, a valve unseating plunger carried by the valve casing, and a plunger actuating lever carried by the valve casing and resting upon the plunger and engaging the well casing. 65

5. In combination, a well casing, a tube therein, a normally closed drain valve carried by the tube, and drain valve opening means carried by the tube and engaging the well casing, said means being mounted for pivotal and radial movements with respect 70 to the tube and casing.

6. In combination, a well casing, a tube therein, a normally closed drain valve carried by the tube and provided with a valve unseating plunger, and a plunger actuating lever carried by the tube and provided with a cam, and adapted to engage the casing. 80

7. In combination, a well casing, a tube therein, a normally closed drain valve carried by the tube and provided with a valve unseating plunger, and a plunger operating lever connected to the tube for pivotal and radial movements with respect thereto and to the casing, the lever being provided with a cam, and a spring urging the lever in the 90 direction of the casing.

8. In combination, a well casing, a tube therein, a normally closed drain valve carried by the tube and provided with a valve unseating plunger, and a plunger actuating lever pivoted to the tube above the plunger and occupying an upwardly and outwardly inclined position with respect to the plunger, the outer end of the lever being in contact with the well casing and said lever being 100 provided below said end thereof with a cam lug. 95

9. In combination, a well casing, a tube therein, a normally closed drain valve carried by the tube and provided with a valve unseating plunger, and a plunger actuating lever pivoted to the tube above and resting upon the upper end of the plunger, the lever occupying an upwardly and outwardly inclined position with respect to the plunger 105 with its outer end in contact with the well casing, and the lever being provided below said end thereof with a cam lug. 110

In testimony whereof I affix my signature.

JOHN A. FRIEND.
